UNITED STATES PATENT OFFICE.

EBER J. HUBBARD, OF BERWYN, ILLINOIS.

SPOOL.

1,365,406.

Specification of Letters Patent. Patented Jan. 11, 1921.

Application filed May 29, 1920. Serial No. 385,101.

To all whom it may concern:

Be it known that I, EBER J. HUBBARD, a citizen of the United States, and a resident of Berwyn, in the county of Cook and State 5 of Illinois, have invented certain new and useful Improvements in Spools, of which the following is a specification.

My invention relates to spools constructed either entirely or in greater part of sheet 10 metal and of such shape and dimensions as to be interchangeable with the ordinary wooden spools heretofore used for holding fine insulated wire or other delicate materials.

15 Wooden spools are rapidly giving way to sheet metal spools. There are sheet metal spools on the market intended for holding wire, but such spools are not practical for holding magnet wire or other fine insulated 20 wire for the reason that the ends of the spools are thin thus permitting them to telescope one with another and chafe or cut the insulation and even the wire itself. Neither do the spools of the prior art possess the required 25 rigidity and strength necessary for holding up under rough usage the spools are apt to receive during winding or unwinding of wire or during shipping or handling thereof. The important object of my invention is therefore to provide strong and rigid end wall construction and connection 30 thereof with the spool body, and end walls of sufficient width to prevent bending thereof and therefore telescopic engagement of 35 one spool with another, thus protecting wire on the spools against chafing or cutting.

The above and other features of my invention are clearly disclosed in the structure shown on the accompanying drawings in 40 which:

Figure 1, is a side elevational view partly in vertical diametral section:

Fig. 2, is an end view partly in section on line 2—2 of Fig. 1, and

45 Fig. 3, is a side elevational view partly in vertical section showing a modified arrangement.

The hub 5 of the spool is formed from a rectangular blank of sheet metal rolled to 50 cylindrical form and with its edges connected together by means of tongues 6 on one edge engaging in dovetail grooves 7 in the opposite edge. Extending from the ends of the hub are the tongues 8 which project 55 through the slots 9 formed in the circular end disks or walls 10, the tongues after in-

sertion through the slots being deflected radially against the outside of the end walls as clearly shown. Extending axially through the hub is the cylindrical core 11 60 also formed of sheet metal, the core ends extending through the openings 12 in the end walls 10 and the material adjacent such openings being deflected outwardly to form cylindrical flanges 13 for receiving the core, 65 these flanges being preferably spot-welded against the core.

The outer peripheral section of each end wall 10 is spun or otherwise deflected outwardly to form the cylindrical flange section 14 for receiving filler material 15 which 70 filler material may be in the form of a wood block, or of paper, mill-board, composition or other material, and may be treated with protective water-proofing, fire-proofing or 75 other material. Each filler block has the center opening 16 for receiving the respective end of the core. After insertion of a 80 filler block the peripheral edge 17 of the flange 14 is deflected radially inwardly against the outside of the filler block and the outer end of the core is flared outwardly as indicated at 18, the filler material being thus 85 securely clamped at its periphery against the respective end wall 10 by the turned edge 17 and at its center being firmly held against the end wall by the flared end 18 of the core. A very rigid structure is thus formed. The tongues 8 may be spot-welded against the 90 respective wall 10 but such spot-welding is 95 really unnecessary as the tongues are so securely clamped against the end walls by the filler material, the tongues sinking into the filler material under the pressure and being thus securely embedded therein and held 100 thereby. The turned edges 17 form a guard to prevent chafing of the filler material when the spool is set on end and the flared ends of the core serve also to permit the spool to be readily applied to a spindle. 100

The filler material gives considerable 105 width to the end structures and such structures are so rigid and so securely connected with the hub and core that it is impossible for spools to telescope. Even if the ends of a spool should bear against the wire on another spool, the rims or flanges 14 are of such width that the insulation would not be injured. In forming the ends care is taken to 110 sufficiently round the corners so that it will be impossible for them to cut or scratch.

In Fig. 3, I have shown a modified ar-

rangement. Instead of inserting non-metallic filler material, the filler structure 19 is constructed of sheet metal comprising a wall having the outer flange 20 and the inner flange 21. The outer flange fits within the flange 14 of the spool side-walls 10 and the inner flange fit the core. After insertion of the filler frame the peripheral section 17 of the rim 14 and the end 18 of the core are deflected in the same manner as in the structure shown in Fig. 1. Where the filler frame is of sheet metal as just described the tongues 8 are preferably spot-welded to the end walls 10.

15 I thus produce a spool which is especially adapted for holding fine insulated wire and which has all the advantages of wooden spools and a great many additional advantages. They are of course of much greater 20 strength than the all wooden spools and are very light. Owing to the improved construction of the end structure the spools cannot telescope and the wire supported thereon is therefore fully protected.

25 Having described my invention I claim as follows:

1. In a spool of the class described, the combination of a hub, a core of sheet metal, end walls having axial openings, said end 30 walls receiving the core ends through their openings and being secured to the ends of the hub, and filler material surrounding the projecting ends of said core, the peripheral sections of said walls being deflected outwardly and downwardly to inclose the peripheral section of said filler material and the outer ends of said core being flared thereby to rivet said filler material against the end walls around the end wall openings.
- 35 2. A spool of the class described comprising a sheet metal hub having tongues at its ends, and walls having slots for receiving said tongues, said tongues extending through said slots and deflected radially against 40 the out-side of said walls, said walls having axial openings, a sheet metal core extending through said openings and through said hub, the peripheral sections of said end walls being deflected outwardly 45 to form cylindrical flanges, filler material interposed between said flanges and the projecting ends of said core, the peripheral

edges of said flanges being deflected radially inwardly against the outer face of said filler material to clamp such filler material at its outer end against the end walls, the outer edges of said core being flared to thereby securely hold the filler material against said end walls at their openings, the clamping engagement of said filler material against 60 said end walls serving to lock said hub tongues against said end walls.

3. A spool of the class described comprising a sheet metal hub, end walls of sheet metal secured to the hub ends concentric therewith, said end walls having axial openings, a sheet metal core extending through said hub and projecting through said openings beyond said walls, said end walls around said openings having flanges for engaging with said core and being spot-welded thereto, the peripheral sections of said end walls being deflected outwardly to form cylindrical flanges, filler material applied between said flanges and the projected ends 70 of the core, the peripheral sections of said flanges and said core being deflected against the outer faces of said filler material whereby such material is securely clamped in position.

4. A sheet metal spool comprising a hub bent into cylindrical form from sheet metal, tongues at the ends of said hub, end plates having slots therethrough for receiving said tongues, said tongues after insertion 85 through said slots being bent over against the outer faces of said plates, said plates having axial openings, a core bent up of sheet metal extending through said hub and projecting through said plate openings a 90 distance outwardly therefrom, each end plate having a flange surrounding its opening and intimately receiving the respective end of said core, said flanges and core being spot-welded together, said end plates at their 95 outer section being deflected laterally to form cylindrical rims, a filler frame inserted within the rim of each end plate and receiving the projecting end of the core, and means for securing said filler frames 100 to said end plates.

In witness whereof, I hereunto subscribe my name this 27th day of May, A. D. 1920.
EBER J. HUBBARD.
